(57) **CLAIM**

The ornamental design for an LED aisle lens, as shown and described.

DESCRIPTION

FIG. 1 is a perspective view of the LED aisle lens.

FIG. 2 is a front plan view of the LED aisle lens, the rear plan view being substantially identical.

FIG. 3 is a left side view of the LED aisle lens, the right side view being substantially identical.

FIG. 4 is a top plan view of the LED aisle lens; and,
FIG. 5 is a bottom plan view of the LED aisle lens.

The bottom view and elements illustrated in phantom are not ornamental and do not constitute part of the claimed design.
